APPARATUS FOR THE CONTROL OF HIGHWAY CROSSING SIGNALS

Paul H. Crago, Wilkinsburg, Pa., assignor to The Union Switch & Signal Company, Swissvale, Pa., a corporation of Pennsylvania

Application July 22, 1938, Serial No. 220,693

16 Claims. (Cl. 246—130)

My invention relates to apparatus for the control of highway crossing signals, and particularly to apparatus for controlling a highway crossing signal located at the intersection of a highway and a railway track over which trains move in both directions.

An object of my invention is the provision, in apparatus of the character described, of novel and improved means for operating the highway crossing signal until trains completely clear the intersection. Other objects and advantages of my invention will appear as the specification progresses.

The apparatus for the control of highway crossing signals set forth in the present application is somewhat similar to that disclosed in a copending application Serial No. 240,521 filed on November 15, 1938, by Henry S. Young for Apparatus for the control of highway crossing signals, and certain features set forth in the present application are broadly covered in the said copending application.

I shall describe two forms of apparatus each embodying my invention, and shall then point out the novel features thereof in claims.

In the accompanying drawing, Fig. 1 is a diagrammatic view showing one form of apparatus embodying my invention. Fig. 2 is a diagrammatic view showing a modified form of the apparatus of Fig. 1 and also embodying my invention.

Referring to Fig. 1, the reference characters 1 and 1a designate the track rails of a stretch of railway over which traffic moves in both directions. Rails 1 and 1a are divided by means of the usual insulated track joints 2 into relatively long operating sections D—E and F—G which are separated from each other by a relatively short positive operating section E—F. Section E—F is intersected by a highway H; and located adjacent the intersection is a highway crossing signal S, which may be any one of the well-known forms, but which, as shown here, is an audible signal in the form of an electric bell. Sections D—E and F—G usually will be of such length that an adequate warning period for highway users of the approach of the train to the highway is provided. Section E—F usually will be of such length that the section completely includes the highway intersection.

Sections D—E and F—G are each provided with a track circuit comprising a track battery 3 connected across the track rails at one end of each section and a track relay, designated by the reference characters TR1 and TR3, respectively, connected across the track rails at the other end.

Section E—F is also provided with a track circuit which may be traced from one terminal of battery 3 of section E—F through rail 1, wire 8, then through four branch paths to wire 9; a first path of which comprises front "flagman" contacts 4 and 5 of an interlocking relay IR, to be referred to later; a second path of which comprises front contacts 7 and 6 of relays TR3 and TR1, respectively; a third path of which comprises front "flagman" contact 4 of relay IR and front contact 6 of relay TR1; and a fourth path of which comprises front contact 7 of relay TR3 and front "flagman" contact 5 of relay IR; wire 9, the winding of relay TR2, wire 10, and rail 1a to the other terminal of battery 3 of section E—F.

The interlocking relay IR, referred to previously, may be of any suitable type, such as, for example, the relay covered by United States Letters Patent No. 1,799,629, granted to W. K. Lockhart and T. J. O'Meara on April 7, 1931. This type of relay is well known and is characterized by the fact that when the left-hand winding W1 is deenergized, the downward movement of the armature associated therewith operates a mechanical locking device which keeps the armature associated with the right-hand winding W2 "locked up" in approximately its mid position, so that a subsequent deenergization of winding W2 while winding W1 is still deenergized cannot close back contacts 4a, 12 and 13. Similarly, if the right-hand winding W2 is first to become deenergized, then back contacts 5a, 14 and 15 are prevented from closing when the left-hand winding W1 becomes deenergized during the interval that winding W2 is still deenergized. Relay IR is also provided with front contacts 5 and 4 associated with windings W1 and W2, respectively, which have what I shall term "flagman" adjustment. That is to say, these contacts remain closed when the associated armature is in its "locked up" position. Winding W1 of relay IR is energized over a circuit passing from one terminal B of a suitable source of current, such as a battery not shown, through front contact 16 of relay TR2, front contact 17 of relay TR1, and winding W1 of interlocking relay IR to the other terminal C of the source of current. Winding W2 is energized over a circuit passing from terminal B through front contact 18 of relay TR3 and the winding W2 of interlocking relay IR to terminal C. As will be explained hereinafter, the interlocking relay IR functions as directional means for preventing the operation of the crossing signal by relay TR1 or TR3 when section D—E or

F—G becomes occupied by trains receding from the intersection.

Signal S is energized over a circuit passing from terminal B through three branch paths to the operating element of signal S and to terminal C, a first path including back contact 15 of winding W1 of relay IR; a second path including back contact 13 of winding W2 of relay IR; and a third path including back contact 19 of relay 10 TR2.

A shunt path, controlled jointly by track relay TR2 and winding W2 of relay IR, is provided around the operating winding of relay TR1 and may be traced from the left-hand terminal of relay TR1 through wire 20, back contact 12 of winding W2 of relay IR, wire 21, back contact 22 of relay TR2, and wire 23 to the right-hand terminal of relay TR1. Similarly, a shunt path, controlled jointly by track relay TR2 and winding 15 W1 of relay IR, is provided around the winding of relay TR3 and may be traced from the right-hand terminal of relay TR3 through wire 24, back contact 25 of relay TR2, back contact 14 of winding W1 of relay IR, and wire 27 to the left-hand terminal of relay TR3.

The apparatus is in its normal condition, as shown in Fig. 1, when sections D—E, E—F and F—G are unoccupied. In this condition of the apparatus, the track relays TR1, TR2 and TR3 30 are energized, windings W1 and W2 of relay IR are likewise energized, and signal S is deenergized. I shall now assume that an eastbound train, that is, a train moving from left to right in Fig. 1, enters section D—E and thereby shunts relay TR1 so that relay TR1 releases. The release of relay TR1 opens front contact 17 and thereby opens the circuit for winding W1 so that winding W1 releases to establish the energizing circuit for signal S at back contact 15. Signal S now becomes energized and exhibits its warning to highway users of the approach of the train.

It is to be noted that when relay TR1 releases, front contact 6 of relay TR1 opens to open the previously mentioned second and third branch 45 paths provided in the track circuit for section E—F; and that when winding W1 releases, front contact 5 of winding W1 opens to open the first and fourth branch paths provided in the track circuit for section E—F, so that relay TR2 releases. It should further be noted that back contact 14 also closes when winding W1 releases so that when back contact 25 of relay TR2 closes, the shunt path around the winding of relay TR3 is completed, whereupon relay TR3 releases to open 55 front contact 18 so that winding W2 of relay IR is deenergized and releases. It should further be noted that back contact 19 of relay TR2 closes to complete the third branch path in the circuit for signal S. It follows that when an eastbound 60 train enters section D—E, relay TR1 is shunted and releases. The release of relay TR1 opens the circuit for winding W1 whereby winding W1 releases to its full released position and initiates the operation of signal S. The release of relay TR1 and winding W1 opens the track circuit for section E—F so that relay TR2 releases to establish the shunt path around the winding of relay TR3 in the track circuit for section F—G so that 65 relay TR3 releases. The release of relay TR3 opens the circuit for winding W2 so that the armature associated with that winding is released and is engaged by the locking feature of relay IR.

When the train enters track section E—F, the 75 wheels and axles of the train shunt the track

rails, but this action serves no useful purpose at this time, since track relay TR2 is released.

When the train vacates section D—E, relay TR1 picks up since its shunt path around its operating winding is open at back contact 12 of winding W2 of relay IR, to close front contacts 6 and 17. Front contact 17 now prepares the circuit for winding W1, but winding W1 is retained released since its energizing circuit is open at front contact 16 of relay TR2. Front contact 6 of relay TR1 completes the third branch path provided in the track circuit for section E—F, but relay TR2 is retained released by the shunt provided across rails 1 and 1a of section E—F by the wheels and axles of the train. The reason for open-circuiting the track circuit for section E—F will now become apparent, since this open-circuiting effects the release of relay TR2 prior to the train entering section E—F. It follows that since relay TR2 is released prior to the entrance of the train on section E—F, the train need not create the low resistance shunt to the rails of section E—F necessary to effect the release of track relay TR2, but need create only sufficient shunting to prevent the pick-up of relay TR2.

When the train enters track section F—G the wheels and axles of the train shunt the rails 1 and 1a of section F—G, but at this time no useful purpose is served, the relay TR3 having been released in response to the release of relay TR2 and winding W1.

When the train vacates track section E—F and completely clears highway H, relay TR2 picks up over its energizing circuit including the previously mentioned third branch path to close front contact 16 and to open back contacts 19, 22 and 25. The opening of back contact 19 of relay TR2 opens the third branch path in the energizing circuit for signal S; and the closing of front contact 16 completes the circuit for winding W1 so that winding W1 becomes energized. Front contact 5 of winding W1 now closes and back contacts 14 and 15 open. The opening of back contact 15 of relay W1 opens the first branch path in the circuit for signal S with the result that signal S ceases to exhibit its warning. It should be noted that back contact 25 of relay TR2 and back contact 14 of winding W1, which are interposed in the shunt path around the winding of relay TR3, are now open, but relay TR3 50 is retained deenergized by virtue of the train shunt in section F—G. The reason for providing the shunt path around the winding of relay TR3 will now become apparent, since the release of relay TR3, resulting from the releasing of relay TR1 and winding W1 when the train enters section D—E, effects the release of winding W2 and consequent "locking up" of the armature of winding W2 to establish directional control of signal S prior to the train shunting the track relay TR3 55 by entering section F—G. It follows that loss of directional control is avoided in the event a train such as a light engine passes rapidly from section E—F to section F—G, since winding W1 cannot become reenergized prior to winding W2 60 becoming deenergized. It can be seen that the directional control for the signal, whereby relay TR3 is prevented from operating the signal when the train occupies section F—G in receding from the intersection, is established when the train first 65 enters the operating section D—E in approaching the intersection, and false operation of the signal due to loss of directional control is prevented.

When the train vacates section F—G, relay 75

TR3 becomes energized to close front contacts 7 and 18, winding W2 picking up over front contact 18. The apparatus is now restored to its normal condition.

5 The operation of the apparatus of Fig. 1 for a westbound train is similar to that just described for an eastbound train. That is to say, the entrance of a westbound train upon section F—G shunts relay TR3 so that relay TR3 releases to open front contact 7 and thereby open the second and fourth branch paths provided in the track circuit for section E—F, and to open front contact 18, thereby opening the circuit for winding W2 of relay IR. Winding W2 now releases to establish the energizing circuit for signal S at back contact 13, and signal S becomes energized to display its warning to highway users. The release of winding W2 also closes back contact 12, thereby preparing the shunt path around the winding of relay TR1, and opens front "flagman" contact 4 to open the first and third branch paths provided in the track circuit for section E—F. The track circuit for section E—F now being open-circuited, relay TR2 releases, thereby opening front contact 16 to open the circuit for winding W1 whereby winding W1 releases its armature to its "locked up" position. The release of relay TR2 also closes back contacts 19, 22 and 25. The closing of back contact 19 completes the third branch path in the circuit for signal S, and the closing of back contact 22 completes the short circuit path around the winding of relay TR1 whereby relay TR1 releases. It follows that when a westbound train enters section F—G, relay TR3 and winding W2 are released, thereby initiating the operation of signal S, and relay TR2 is released to insure that signal S will operate until the train vacates section E—F and clears the highway. Also, relay TR1 and winding W1 are released so that the armature of winding W1 is engaged by the interlocking feature of relay TR, thus avoiding possible loss of the directional control for signal S.

When the train enters section E—F and establishes the train shunt across the rails of section E—F, no useful purpose is served by this train shunt at this time since relay TR2 is released when the train enters section F—G.

Ordinarily, the head end of the train enters section D—E to shunt relay TR1 prior to the rear of the train vacating section F—G. Under this ordinary condition, the entrance of the train on section D—E establishes the train shunt in section D—E. The train shunt in section D—E, however, serves no useful purpose at this time since relay TR1 is released when the train enters section F—G. Hence, under the ordinary conditions, when the train vacates section F—G, relay TR3 picks up to close front contacts 7 and 18. The closing of front contact 7 completes the fourth branch path provided in the track circuit for section E—F, but relay TR2 is now held deenergized by the train shunt in section E—F. The closing of front contact 18 completes the energizing circuit for winding W2. Winding W2 now picks up to open back contact 13 and thereby opens the second branch path in the circuit for signal S, but signal S is retained energized over its branch circuit including back contact 19 of relay TR2. Back contact 12 also opens when winding W2 picks up, thereby opening the shunt path around the winding of relay TR1, but relay TR1 is now held released by the train shunt in section D—E. When the train vacates section E—F and clears the intersection, relay TR2 picks

up to open back contact 19, thereby terminating the operation of signal S, and to close front contact 16 to prepare the circuit for winding W1. When the train vacates section D—E, relay TR1 picks up to close front contact 17, thereby completing the circuit for winding W1 so that winding W1 picks up.

In the event that the train is short, so that the rear of the train vacates section F—G prior to the head end entering section D—E, a further function arises for open-circuiting the track circuit for section E—F whereby relay TR2 releases. When a train is short enough to be entirely within section E—F so that it vacates section F—G and thus permits relay TR3 and winding W2 to pick up prior to the train entering section D—E, relay TR1 will also pick up since the picking up of winding W2 removes the shunt path around the winding of relay TR1, and relay TR1 is not yet shunted by the train. The picking up of relay TR1, however, does not complete the energizing circuit for winding W1 since that circuit is open at front contact 16 of relay TR2, so that winding W1 remains released and maintains the directional control for signal S. When the short train enters section D—E, relay TR1 is shunted and releases to open the circuit for winding W1 at front contact 17. When the train vacates section E—F, relay TR2 picks up, opening back contact 19 and thereby opening the circuit for signal S to terminate the operation of signal S, and closing front contact 16 to prepare the circuit for winding W1. When this short train vacates section D—E, relay TR1 picks up to close front contact 17 to complete the circuit for winding W1 so that winding W1 picks up.

It follows that for a westbound train, the open-circuiting of the track circuit for section E—F results in providing the condition that a low resistance train shunt is not required to release relay TR2, the same as for an eastbound train, and relay TR2 released provides the function of retaining the established directional control for a train short enough to be entirely within section E—F. Furthermore, when a westbound train passes rapidly from section F—G to sections E—F and D—E, loss of directional control is avoided since winding W1 is deenergized and released while the train is approaching the intersection in section F—G.

It is to be understood that while I have shown (in Fig. 1) relay TR2 as being controlled by relay TR1 or TR3 open-circuiting the track circuit for section E—F, relay TR2 may be controlled by any other suitable means, such as by providing a short circuit path around the winding of relay TR2, this short circuit path being controlled by relay TR1 or TR3.

It should be noted that relay IR is provided with contacts 5a and 4a associated with windings W1 and W2, respectively, and suitably interconnected so that in the event relays TR1 and TR3 might accidentally be released at the same instant, thereby permitting both windings W1 and W2 of relay IR to assume their full released positions, relay TR2 is not open-circuited and does not release to complete the shunt paths around relays TR1 and TR3. It follows that when the conditions causing the simultaneous release of relays TR1 and TR3 are removed, relays TR1 and TR3 will again become reenergized.

Referring now to Fig. 2, the track circuit for section D—E may now be traced from one terminal of battery 3 of section D—E through rail 1, wire 28, the winding of relay TR1, wire 29,

then through two branch paths to wire 30; one path comprising wire 29a, front contact 31 of relay TR2 and wire 30a; the other path comprising wire 29b, front "flagman" contact 32 of winding W2 of relay IR and wire 30b; wire 30, and rail 1a to the other terminal of battery 3. The track circuit for section F—G may be traced from one terminal of battery 3 of section F—G through rail 1, wire 33, winding of relay TR3, wire 34, then two branch paths to wire 35; one path comprising wire 34a, front contact 36 of relay TR2 and wire 35a; the other path comprising wire 34b, front "flagman" contact 37 of winding W1 of relay IR and wire 35b; wire 35 and rail 1a to the other terminal of battery 3. The track circuit for section E—F may be traced from one terminal of battery 3 of section E—F, through wire 38, rail 1, the winding of relay TR2, rail 1a, wire 39, then two branch paths to wire 40; one branch path comprising wire 41, front contact 6 of relay TR1, and wire 43; the other branch path comprising wire 44, front "flagman" contact 5 of winding W1 of relay IR, and wire 46; wire 40, then two branch paths to wire 47; one path comprising wire 48, front contact 7 of relay TR3, and wire 50; the other path comprising wire 51, front "flagman" contact 4 of winding W2 of relay IR, and wire 53; wire 47 and regulating resistance R to the other terminal of battery 3.

Winding W1 of relay IR is provided with a pick-up circuit passing from terminal B through front contact 16 of relay TR2, front contact 17 of relay TR1, and the winding W1 of relay IR to terminal C. Winding W2 is similarly provided with a pick-up circuit passing from terminal B through front contact 16 of relay TR2, front contact 18 of relay TR3 and the winding W2 of relay IR to terminal C. Windings W1 and W2 are each provided with stick circuits; a stick circuit for winding W1 passing from terminal B through front "flagman" contact 57 of winding W1, front "flagman" contact 58 of winding W2, front contact 17 of relay TR1 and winding W1 to terminal C; and a stick circuit for winding W2 passing from terminal B through front "flagman" contact 57 of winding W1, front "flagman" contact 58 of winding W2, front contact 18 of relay TR3, and winding W2 to terminal C.

The operating circuit for signal S is the same as traced for Fig. 1, except that front "flagman" contact 57 of winding W1 is interposed in the branch circuit governed by back contact 13 of winding W2.

In the normal condition of the apparatus, that is, when sections D—E, E—F and F—G are unoccupied, the apparatus is in the condition shown in Fig. 2. In this normal condition, relays TR1, TR2 and TR3 are energized; the pick-up and stick circuits for windings W1 and W2 of relay IR are completed so that both windings of relay IR are energized; and signal S is deenergized.

I shall now assume that an eastbound train enters section D—E of Fig. 2 so that relay TR1 is shunted and releases to open front contact 17. This opens both the pick-up and stick circuits for winding W1 of relay IR, and winding W1 releases to complete the circuit for signal S over back contact 15. Signal S is now energized, and displays its warning to traffic operating on the highway H. Front contact 6 also opens when relay TR1 releases, and front contact 5 likewise opens when winding W1 releases. The opening 75 of these contacts, which are interposed in the

track circuit for section E—F between wires 39 and 40, opens that track circuit so that relay TR2 also releases. The release of relay TR2 opens front contacts 31, 36 and 16, and closes back contact 19, the latter of which completes its branch path for signal S.

The opening of front contact 36 of relay TR2 (front contact 37 of winding W1 being opened when winding W1 releases) opens the track circuit for section F—G so that relay TR3 releases to open front contacts 7 and 18, the opening of the latter contact opening both the pick-up and stick circuits for winding W2 so that winding W2 also releases. It follows that when an eastbound train enters section D—E, relay TR1 and winding W1 release, thereby initiating the operation of signal S, and establishing directional control thereof. The release of relay TR1 and winding W1 also opens the track circuits for sections E—F and F—G so that relays TR2 and TR3 release. The release of relay TR2 opens the circuit for winding W2 so that the armature associated with winding W2 is released and engaged by the locking feature of relay IR.

When the train enters track section E—F, the wheels and axles of the train shunt the track rails, but this action serves no useful purpose at this time.

When the train vacates section D—E, relay TR1 becomes energized and closes front contacts 6 and 17, the closing of front contact 6 completing the circuit for relay TR2 across wires 39 and 40, but relay TR2 is retained deenergized by the train shunt in section E—F. As was explained hereinbefore, since the release of relay TR2 is effected by the train entering section D—E, the train need not create the low resistance shunt to the track rails of section E—F necessary to release relay TR2, but need only provide sufficient shunting to prevent the pick-up of relay 40 TR2. It should be noted that since battery 3 of section E—F is disconnected from the track rails of section E—F when the train occupies section D—E, a saving in battery current is effected.

When the train enters track section F—G, the wheels and axles of the train shunt the track rails, but no useful function is served at this time by this action. When the train vacates section E—F, and completely clears highway H, relay TR2 becomes reenergized to close front contacts 31, 36 and 16 and to open back contact 19, the latter contact opening the third branch path in the circuit for signal S. The closing of front contact 16 of relay TR2 completes the pick-up circuit for winding W1 so that winding W1 becomes reenergized to open back contact 15 and thereby open the circuit for signal S, and to close front contacts 5, 37 and 57, the last contact completing the stick circuit for winding W1. Signal S now becomes deenergized and no longer displays its warning exhibit to highway traffic. Relay TR3 is now held deenergized by virtue of the train shunt in section F—G, since front contact 36 of relay TR2 and front contact 37 of winding W1 are now closed so that each now completes the track circuit for the section F—G across wires 34 and 35. As was pointed out previously in connection with Fig. 1, the release of relay TR3 is effected by the release of relay TR1 and winding W1 to insure that when a light engine passes rapidly from section E—F to section F—G, winding W2 is deenergized and engaged by the interlocking feature of relay IR prior to winding W1 becoming energized, thereby avoiding possible loss of directional control of signal S. 75

When the train vacates section F—G, relay TR3 becomes reenergized to close front contacts 7 and 18, the closing of front contact 18 completing the pick-up and stick circuits for winding W2 so that winding W2 becomes reenergized. The apparatus is now in its normal condition.

The operation of the apparatus of Fig. 2 for a westbound train is similar to that just described for an eastbound train. That is to say, a westbound train entering section F—G initiates the operation of signal S and establishes directional control by releasing relay TR3 and winding W2 of relay IR. Also, the track circuits for sections D—E and E—F are opened so that relays TR2 and TR1 release; and the circuit for winding W1 is opened whereby winding W1 releases to its locked position. When the train vacates section F—G, relay TR3 becomes reenergized, but signal S is retained energized by virtue of its circuit controlled by back contact 13 of winding W2 of relay IR since winding W2 is controlled by relay TR2. When the train completely passes highway H and vacates section E—F, relay TR2 and winding W2 of relay IR pick up to stop the operation 25 of signal S. Then, when the train vacates section D—E, relay TR1 and winding W1 of relay IR become reenergized, and the apparatus is restored to its normal condition.

It is to be noted that windings W1 and W2 are each provided with a stick circuit so that an accidental shunting of track relay TR2, and consequent opening of the pick-up circuits for windings W1 and W2, does not deenergize windings W1 and W2. Thus, it can be seen that a winding 30 of relay IR can only become released when the track relay associated with that winding is released to interrupt both the pick-up and stick circuits for that winding. It should further be noted that relay IR is provided with back contacts 5a and 4a, associated with windings W1 and W2, respectively, which are suitably connected so that an accidental shunting at the same instant of both track relays TR1 and TR3, resulting in the simultaneous release of both windings W1 35 and W2 to their full released position, does not open-circuit relay TR2 with the result that relay TR2 does not release. Since relay TR2 does not release, relays TR1 and TR3 are not open-circuited at front contacts 31 and 36, respectively, 40 of relay TR2, so that when the shunt is removed from the windings of relays TR1 and TR3, they will again become reenergized.

One advantage of apparatus embodying my invention is the provision of novel and improved means effective to operate a highway crossing signal protecting the intersection of a highway and a railway track over which traffic moves in both directions until trains completely clear the intersection.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a stretch of railway track divided into a first section and a third section 70 separated from each other by a second section intersected by a highway, a highway crossing signal located at such intersection, a first track relay associated with said first section, a second track relay associated with said second section, a third track relay associated with said third sec-

tion, directional means controlled by said first and third track relays for causing said signal to operate whenever a train is approaching the intersection, circuit means governed by said first and third track relays and by said directional means for causing said second track relay to release whenever a train is approaching the intersection and prior to such train entering said second section, and means controlled by said second track relay for controlling said directional means 10 to cause said signal to operate until the train clears the intersection.

2. In combination, a stretch of railway track divided into a first section and a third section 15 separated from each other by a second section intersected by a highway, a highway crossing signal located at such intersection, a track circuit for said first section including a first track relay, a track circuit for said second section including a second track relay, a track circuit for 20 said third section including a third track relay, operating means governed by said first relay or said third relay and operative according as said first section or said third section is first entered by a train approaching the highway for operating said signal, circuit means governed by said first relay or said third relay and operative according as said first section or said third section is first entered by a train approaching the highway for open-circuiting said second track circuit, 25 and other operating means governed by said second relay for operating said signal.

3. In combination, a stretch of railway track divided into a first section and a third section 30 separated from each other by a second section intersected by a highway, a highway crossing signal located at such intersection, a first track relay associated with said first section, a second track relay associated with said second section, a third track relay associated with said third section, 35 means controlled by said first track relay and effective when said first track section is entered by a train approaching the highway for initiating the operation of said signal and for releasing said second track relay and said third track relay, means controlled by said second track relay to operate said signal, and means controlled by said third track relay and effective when said third section is entered by a train approaching the highway for initiating the operation of the 40 signal and for releasing said second track relay and said first track relay.

4. In combination, a stretch of railway track divided into a first operating section and a second operating section separated by a positive operating section, said positive operating section intersected by a highway, a signal for controlling traffic on said highway at such intersection, a first track relay associated with said first operating section, a second track relay associated with 50 said second operating section, a third track relay associated with said positive operating section, operating means initiated by a train entering either one of said operating sections when approaching the highway for operating said signal, 55 means controlled by the track relay associated with said one of said operating sections for releasing the track relay associated with the other of said operating sections and said third track relay, means controlled by said third track relay for governing said operating means to operate said signal until the train clears the highway, 60 and directional means controlled by the track relays associated with said operating sections for preventing the train from operating said signal 65 75

when receding from the highway through either of said operating sections.

5. In combination, a stretch of railway track divided into a first section and a third section 5 separated from each other by a second section intersected by a highway, a highway crossing signal located at such intersection, an interlocking relay having a first winding and a second winding, a first circuit for said signal governed by a 10 back contact of said first winding, a second circuit for said signal governed by a back contact of said second winding, a first track relay associated with said first track section for controlling said first winding of the interlocking relay, a second 15 track relay associated with said second track section, a third track relay associated with said third track section for controlling said second winding of the interlocking relay, a third circuit for said signal governed by a back contact of said 20 second track relay, means governed jointly by said first track relay and said first winding of the interlocking relay operative to release said second track relay and said third track relay, and means governed jointly by said third track relay and 25 said second winding of the interlocking relay operative to release said second track relay and said first track relay.

6. In combination, a stretch of railway track divided into a first section and a third section 30 separated from each other by a second section intersected by a highway, a highway crossing signal located at the intersection, an interlocking relay having a first winding and a second winding, a first energizing circuit for said signal controlled 35 by back contact of each winding of the interlocking relay, a first track relay associated with said first track section, an energizing circuit for said first winding of the interlocking relay including a front contact of said first relay, a third track relay associated with said third track circuit, an energizing circuit for said second winding of the interlocking relay including a front contact of said third relay, a second track relay associated with said second track section, a second 40 energizing circuit for said signal including a back contact of said second track relay, means controlled jointly by said first track relay and said first winding of the interlocking relay operative to release said second track relay and said 45 third track relay whenever a train first enters said first section in approaching the intersection, and means controlled jointly by said third track relay and said second winding of the interlocking relay operative to release said second track relay and said 50 first track relay whenever a train first enters said third section in approaching the intersection.

7. In combination, a stretch of railway track provided with a first section and a third section 60 separated from each other by a second section intersected by a highway, a highway crossing signal located at such intersection, an interlocking relay having a first winding and a second winding, a first circuit for said signal governed 65 by a back contact of said first winding or of said second winding of the interlocking relay, a first track relay associated with said first section for governing said first winding of the interlocking relay, a second track relay associated with said 70 second section, a third track relay associated with said third section for governing said second winding of the interlocking relay, means including a front contact of said first relay and a front contact of said first winding of the interlocking relay for controlling said second relay,

other means including a front contact of said third relay and a front contact of said second winding of the interlocking relay for controlling said second relay, a second circuit for said signal including a back contact of said second relay, and means including back contacts of said second relay for controlling said first and said third relays.

8. In combination, a stretch of railway track divided into a first section and a third section 10 separated from each other by a second section intersected by a highway, a highway crossing signal located at such intersection, a track circuit for said first section including the winding of a first track relay, a track circuit for said second section including the winding of a second track relay, a track circuit for said third section including the winding of a third track relay, operating means governed by said first relay or said third relay and effective according as said first 15 section or said third section is first entered by a train approaching the intersection for operating said signal, other operating means governed by said second track relay for operating said signal, circuit means governed by said first track relay or said third track relay and effective according as said first section or said third section is first 20 entered by the train approaching the intersection to open-circuit said second track circuit, other circuit means governed by the one of said 25 first and said third track relays associated with the track section entered by the train in approaching the intersection for providing a short circuit path around the winding of the other one of said first and said third track relays, and directional means governed by said first and said third track relays.

9. In combination, a stretch of railway track divided into a first section and a third section 30 separated from each other by a second section intersected by a highway, a highway crossing signal located at such intersection, a track circuit for said first section including a first track relay, a track circuit for said second section including a second track relay, a track circuit for said third section including a third track relay, operating means governed by said first track relay or said third track relay and effective according as said first section or said third section is first entered by a train approaching the intersection for operating said signal, other operating means governed by said second track relay for operating said signal, circuit means governed by said first track relay or said third track relay and effective according as said first section or said third section is first entered by a train approaching the intersection to open-circuit said second track circuit, directional means governed by said first track relay and said third track relay, and other circuit means governed by said first track relay or said third track relay and effective according as said first section or said third section is first entered by the train approaching the intersection for open-circuiting said second track circuit, 40 directional means governed by said first track relay and said third track relay, and other circuit means governed by said first track relay or said third track relay and effective according as said first section or said third section is first entered by the train approaching the intersection for open-circuiting said second track circuit, 45 directional means governed by said first track relay and said third track relay, and other circuit means governed by said first track relay or said third track relay and effective according as said first section or said third section is first entered by the train approaching the intersection for open-circuiting said second track circuit, 50 directional means governed by said first track relay and said third track relay, and other circuit means governed by said first track relay or said third track relay and effective according as said first section or said third section is first entered by the train approaching the intersection for open-circuiting said second track circuit, 55 directional means governed by said first track relay and said third track relay, and other circuit means governed by said first track relay or said third track relay and effective according as said first section or said third section is first entered by the train approaching the intersection for open-circuiting said second track circuit, 60 directional means governed by said first track relay and said third track relay, and other circuit means governed by said first track relay or said third track relay and effective according as said first section or said third section is first entered by the train approaching the intersection for open-circuiting said second track circuit, 65 directional means governed by said first track relay and said third track relay, and other circuit means governed by said first track relay or said third track relay and effective according as said first section or said third section is first entered by the train approaching the intersection for open-circuiting said second track circuit, 70 directional means governed by said first track relay and said third track relay, and other circuit means governed by said first track relay or said third track relay and effective according as said first section or said third section is first entered by the train approaching the intersection for open-circuiting said second track circuit, 75

10. In combination, a stretch of railway track divided into a first section and a third section separated from each other by a second section intersected by a highway, a highway crossing signal located at such intersection, an interlocking relay having a first winding and a second winding, a first energizing circuit for said signal governed by a back contact of each winding of the interlocking relay, a track circuit for said first section including the winding of a first track

- relay, said first relay governing said first winding of the interlocking relay, a track circuit for said third section including the winding of a third track relay, said third track relay governing said second winding of the interlocking relay, a track circuit for said second section including the winding of a second track relay, a second energizing circuit for said signal including a back contact of said second relay, means governed 5 jointly by said first relay and said first winding of the interlocking relay and effective whenever a train first enters said first section in approaching the intersection for open-circuiting said second track circuit, other circuit means governed 10 jointly by said third track relay and said second winding of the interlocking relay and effective whenever a train first enters said third section in approaching the intersection for open-circuiting said second track circuit, a short circuit path 15 around the winding of said first relay serially including a back contact of said second relay and a back contact of said second winding of the interlocking relay, and a short circuit path around the winding of said third relay serially including 20 a back contact of said second relay and a back contact of said first winding of the interlocking relay.
11. In combination, a stretch of railway track divided into a first section and a third section 25 separated from each other by a second section intersected by a highway, a highway crossing signal located at such intersection, an interlocking relay having a first winding and a second winding, a first energizing circuit for said signal 30 including a back contact of each winding of the interlocking relay, a track circuit for said first section including a first track relay, said first relay governing said first winding of the interlocking relay, a track circuit for said third section including a third track relay, said third relay governing said second winding of the interlocking relay, a track circuit for said second section including a second track relay, a second energizing circuit for said signal including a back contact of said second relay, circuit means 35 governed jointly by said first relay and said first winding of the interlocking relay effective whenever a train first enters said first section in approaching said intersection for open-circuiting said second track circuit, other circuit means governed jointly by said third relay and said second winding of the interlocking relay effective whenever a train first enters said third section in approaching said intersection for open-circuiting 40 said second track circuit, means governed jointly by said second track relay and said first winding of the interlocking relay for open-circuiting said first track circuit, and means governed jointly by said second track relay and said first winding of the interlocking relay for open-circuiting said third track circuit.
12. In combination, a stretch of railway track divided into a first section and a third section 45 separated from each other by a second section intersected by a highway, a highway crossing signal located at such intersection, a first track relay associated with said first section, a second track relay associated with said second section, a third track relay associated with said third section, an interlocking relay having a first winding and a second winding, energizing circuit means for said first winding controlled jointly by said first relay and said second relay, energizing circuit means for said second winding controlled 50 jointly by said third relay and said second relay, and an operating circuit for said signal governed by a back contact of each winding of the interlocking relay.
13. In combination, a stretch of railway track divided into a first section and a third section 55 separated from each other by a second section intersected by a highway, a highway crossing signal located at such intersection, a first track relay associated with said first section, a second track relay associated with said second section, a third track relay associated with said third section, an interlocking relay having a first winding and a second winding, said first and second windings each having a pick-up circuit and a stick circuit, said first relay governing both said 60 pick-up and stick circuits of said first winding, said third relay governing both said pick-up and said stick circuits of said second winding, said second relay governing said pick-up circuit of said first winding and said pick-up circuit of said second winding, and an operating circuit for said signal governed by said first winding and by said second winding.
14. In combination, a stretch of railway track divided into a first section and a third section 65 separated from each other by a second section intersected by a highway, a highway crossing signal located at such intersection, a first track relay for said first section, a second track relay for said second section, a third track relay for said third section, an interlocking relay having two windings, operating circuit means controlled by each of said two windings for operating said signal, control circuit means for a first of said two windings controlled jointly by said first track relay and said second track relay, control circuit means for the second of said two windings controlled jointly by said third track relay and said second track relay, circuit means controlled 70 jointly by said first track relay and said first winding and effective whenever a train first enters said first section in approaching the intersection for causing the release of said second track relay, and other circuit means controlled jointly by said third track relay and said second winding and effective whenever a train first enters said third section in approaching the intersection for causing the release of said second track relay.
15. In combination, a stretch of railway track divided into a first section and a third section 75 separated from each other by a second section intersected by a highway, a highway crossing signal located at such intersection, a first track relay for said first section, a second track relay for said second section, a third track relay for said third section, an interlocking relay having two windings, operating circuit means controlled by each of said two windings for operating said signal, control circuit means for a first of said two windings controlled jointly by said first track relay and said second track relay, control circuit means for the second of said two windings controlled jointly by said third track relay and said second track relay, circuit means controlled 80 jointly by said first track relay and said first winding and effective whenever a train first enters said first section in approaching the intersection for causing the release of said third track relay, and other circuit means controlled jointly by said third track relay and said second winding and effective whenever a train first enters said third section in approaching the intersection for causing the release of said first track relay.

16. In combination, a stretch of railway track divided into a first section and a third section separated from each other by a second section intersected by a highway, a highway crossing signal located at such intersection, a first track relay for said first section, a second track relay for said second section, a third track relay for said third section, an interlocking relay having two windings, operating circuit means controlled 5 by each of said two windings for operating said signal, control circuit means for a first of said two windings controlled jointly by said first track relay and said second track relay, control circuit means for the second of said two windings con-

trolled jointly by said third track relay and said second track relay, circuit means controlled jointly by said first track relay and said first winding and effective whenever a train first enters said first section in approaching the intersection for causing the release of said second track relay and said third track relay, and other circuit means controlled jointly by said third track relay and said second winding and effective whenever a train first enters said third section in approaching the intersection for causing the release of said first track relay and said second track relay. 5 10
